CLAIM

I claim the ornamental design for a pet brush with reservoir and hollow bristles for dispensing flea and tick medication, as shown and described.

DESCRIPTION

FIG. 1 is a perspective view of a pet brush with reservoir and hollow bristles for dispensing flea and tick medication showing my new design;

FIG. 2 is a front elevational view thereof;

FIG. 3 is a top plan view thereof;

FIG. 4 is a right side elevational view thereof, the left side elevational view being a mirror image thereof;

FIG. 5 is a rear elevational view thereof;

FIG. 6 is a bottom plan view thereof; and,

FIG. 7 is a perspective view showing the pet brush with reservoir and hollow bristles for dispensing flea and tick medication in use; the broken lines depict environmental structure for illustrative purposes only and form no part of the claimed design.
